WILLIAM P. KEYSER AND JOHN A. MOORE, OF RICHLAND DISTRICT, WEST VIRGINIA.

FEED-REGULATOR FOR POWDERED FUEL.

1,388,185.

Specification of Letters Patent. Patented Aug. 23, 1921.

Application filed June 10, 1919. Serial No. 303,074.

To all whom it may concern:

Be it known that we, WILLIAM P. KEYSER and JOHN A. MOORE, citizens of the United States of America, and residents of Richland district, county of Ohio, and State of West Virginia, have invented certain new and useful Improvements in Feed-Regulators for Powdered Fuel, of which the following is a specification.

10 This invention relates broadly to means for controlling the delivery of air conveyed pulverized material, and more particularly to a feed control valve for powdered-coal feeding systems.

15 The primary object of the invention is to provide, in association with a supply pipe or main conduit through which pulverized or powdered material is conveyed by the impelling force of an air blast, regulatable 20 means whereby the quantity of material diverted from said main conduit to a branch line may be readily controlled.

25 A further object is to provide a regulating device or valve, designed especially for use in systems for supplying finely comminuted coal, commonly termed "coal dust," to furnaces, whereby the rate of feed of the fuel from the supply line or conduit to a branch line or pipe leading to a furnace may 30 be accurately controlled.

35 A still further object is to provide a valve of the character mentioned which may be conveniently and instantly adjusted without in any way interrupting or disturbing the constancy of the flow of fuel through the main conduit.

40 With these and other objects in view, the invention resides in the features of construction, arrangement of parts and combinations of elements which will hereinafter be fully described, reference being had to the accompanying drawings, in which—

45 Figure 1 is a central section of our invention;

Fig. 2 is a side elevation of the collector.

Fig. 3 is a view showing the device connected to a burner.

50 Referring to said drawings, in which like designating characters distinguish like parts throughout the several views—

1 indicates a main conveyer pipe or conduit through which the powdered or comminuted fuel is conveyed in a constant

stream, as ordinarily, by the force of an air current or blast from the suitably located 55 fan or blower. Mounted on said conduit at the point from which it is desired to lead fuel for feeding a furnace is the device which constitutes the present invention, the same including a saddle member 2 which 60 is suitably supported against the under side of said conduit, as by means of a band or bands 3. Said saddle 2 has therein a centrally disposed opening 5 in register with an opening 4 provided in the under side of the 65 conduit. Attached to said saddle is the upper end of a valve casing 6 having therein a conical seat 7 in which is disposed a rotary cone valve 8. Said valve has therein a central vertical bore or socket 9 which registers 70 at its upper end with the openings 4 and 5. Leading laterally outward from said socket 9 through the wall of said valve 8 is a passage or port 10 which is adapted to be carried by rotation of the valve into and out 75 of register with a side opening or passage 11 in the valve casing. Said passage 11 is designed to be disposed in open communication with a branch line or pipe (not shown) leading to a furnace. 80

Fitted closely in the socket 9 is a vertically disposed adjustable tube 12 the upper end of which protrudes through the openings 4 and 5 into the interior of the conduit 1. Said tube has its lower end mounted upon 85 a piston-like plunger 13 carried upon the upper end of a stem 14 which is vertically movable through the lower end of the valve 8. A portion of one side of the upper end of said tube is cut away, as 90 is best shown in Fig. 2, and the remaining approximately semi-cylindrical portion 12^a constitutes a baffle against the internal face of which coal dust passing through the conduit impinges and thence 95 drops downward into the interior of said tube. Said tube has in one side thereof a longitudinally extending port 15 which is so located and which has such a length that a portion thereof registers with the port 10 100 in the valve 8 at all times irrespective of the extent of elevation of said tube.

In practice, the tube 12, which functions as a collector of the pulverized fuel, is adjusted vertically for disposing its upper, or 105 receiving, end at a greater or less elevation

within the conduit 1 for controlling the rate of feed of the fuel. It being understood that the lower stratum of powdered fuel passing through the conduit 1 is quite dense and that the density decreases rapidly from the lower to the upper stratum, it is obvious that the mouth of the collector tube may be disposed by adjustment to receive fuel from strata of any desired density and that, consequently, the rate of feed of fuel to the furnace may be more or less accurately regulated or controlled. Further regulation may be effected by rotating the valve 8 to dispose more or less of the cross sectional area of its port 10 in register with the passage 11 in the valve casing 6.

Since the baffle 12^a has a transverse disposition within the conduit 1 when the ports 15, 10 and 11 are in full registering relation, it is obvious that when the valve is rotated to a position in which a reduction in the cross sectional area of the feed passage is effected, with a corresponding reduction in the capacity of said passage, said baffle will occupy a position diagonal to a transverse conduit-bisecting plane, in which position its capacity or efficacy for intercepting fuel and directing the same downward through the tube is reduced.

While any preferred means may be provided whereby adjustment of the valve and of the collector tube may be accomplished, we have herein shown, for illustrative purposes only, a vertical tube 16 having its upper end fixed to the lower end of the valve 8. Rotation imparted to this tube will obviously be directly communicated to the valve. The stem 14 which carries the plunger 13 extends downward through the interior of and projects outward from the lower end of said tube 16 and has fixed on its end a cross-head 17. Two oppositely disposed levers 18 have their inner ends pivotally mounted at fixed points, as upon lugs 19 carried by a nipple 20 which is threaded upon the lower end of said tube 16. Links 21 pivoted at their lower ends upon the opposite ends of the cross-head 17, have their upper ends pivoted to said levers 18 intermediate the ends of the latter. As is obvious, force applied to the outer ends of said levers, or either of them, will effect, through the intermediate mechanism described, shifting movement of the collector tube, the direction of movement being dependent upon whether the force applied to said levers is directed upwardly or downwardly. As is apparent, said levers may also be employed for effecting rotation of the valve 8.

Manifestly, the present invention is admirably adapted for use in regulating or controlling the feed of fuel in those systems in which the compressed air carrying the fuel is supplied at a constant or uniform ve-

locity. In other words, the invention furnishes a simple and efficient means of control which obviates the necessity for varying the volume of air and which consequently, eliminates those objections which arise from reductions in the volume and velocity of the air below a certain limit, chief among which may be mentioned that the fuel is permitted to collect or pile up, clogging the passages.

What is claimed is—

1. A feed regulator for powdered fuel, comprising a supply conduit for conveying the air and powdered fuel, said conduit having an opening in the under side thereof, a valve casing attached to said conduit and having a cone seat therein, a cone valve rotatable on said seat, a central socket in said valve disposed in register with the opening in the conduit, a tubular member fitted in said socket with its upper end extending into the interior of said conduit for intercepting and conducting downward some of the fuel, and means for adjusting the elevation of said member for disposing the receiving end of the latter at various levels within said conduit, said member and said valve having registering ports, and said valve casing having a discharge passage with which said ports are adapted to register.

2. A feed regulator for powdered fuel, comprising a supply conduit for conveying the air and powdered fuel, said conduit having an opening in the under side thereof, a valve casing attached to said conduit and having a cone seat therein, a cone valve rotatable on said seat, a central socket in said valve disposed in register with the opening in the conduit, a tubular member fitted in said socket with its upper end extending into the interior of said conduit, said upper end of said member having means for intercepting and deflecting fuel downward into the interior of said member, means for adjusting the elevation of said member, said member and said valve and said casing having ports or passages therein, and means for relatively adjusting said elements to dispose said ports or passages in register for discharging the fuel collected by said member.

3. A fuel regulator for powdered fuel, comprising a supply conduit for conveying the air and powdered fuel, said conduit having an opening in the under side thereof, a valve casing attached to said conduit and having a cone seat therein, a cone valve rotatable on said seat, a central socket in said valve disposed in register with the opening in the conduit, a tubular member fitted in said socket with its upper end extending into the interior of said conduit, said upper end of said member having means for intercepting and deflecting fuel downward into the interior of said member, means for ad-

justing the elevation of said member, whereby its said deflecting means may be disposed at various levels within said conduit, said valve casing having a side-opening discharge passage therein, and said valve and said member having registering ports adapted to be disposed in register with said passage, and means for rotating said valve.

In testimony whereof we affix our signatures in presence of two witnesses.
